F. SIEVERN

TOOL

Filed Jan. 7, 1927

UNITED STATES PATENT OFFICE.

FREDRICK SIEVERN, OF MCKEESPORT, PENNSYLVANIA.

TOOL.

Application filed January 7, 1927. Serial No. 159,546.

My invention relates to tools, and is herein-after described as applied more particularly to a wrench having a plurality of bars each provided with nut-engaging portions, although such portions may be modified to serve as tools of other types.

In various types of multipart wrenches having fixed nut-engaging jaws, as heretofore constructed, difficulty has been experienced in providing, within a compact space, a sufficient number of nut-engaging members, and difficulty has also been experienced in providing a structure wherein sufficient strength and leverage is provided. Also, some of such wrenches are not conveniently operable to turn a nut in both directions, and others are of such form that they can not be brought into proper radial alinement with a nut to be operated upon.

My invention has for its object the provision of an improved form of wrench wherein the foregoing objections are either partially or entirely eliminated, and to simplify and improve the structure and arrangement of combination tools generally.

Some of the forms which my invention may take are shown in the accompanying drawing, wherein Figure 1 is a plan view of a tool embodying my invention; Fig. 2 is an inverted plan view of the structure of Fig. 1; Fig. 3 is a view, taken on the line III—III of Fig. 1; Fig. 4 is a cross sectional view, similar to that of Fig. 3, but showing a modified form of tool; Fig. 5 is a plan view of still another modification embodying my invention; Fig. 6 is a view taken on the line VI—VI of Fig. 5; Fig. 7 is a plan view of still another form of tool, and Fig. 8 is a view taken on the line VIII—VIII of Fig. 7.

Referring now to Figs. 1, 2 and 3, I show a wrench structure having a body portion 10 whose ends are recessed at 11 and 12, for engaging nuts of larger sizes. The body portion is provided with pairs of flanges 13 and 14, whose free edges are turned in slightly as indicated more clearly in Fig. 3, to engage the edges of slide bars 15 and 16, which edges are beveled or of approximately dove-tail form. The bars 15 and 16 are provided with slots into which pin-like bosses 17 extend, such bosses being formed integrally with or suitably secured to the main bar 10. The bosses 17 limit sliding movements of the bars 15 and 16, by engagement with the end walls of the slots of said bars.

The bar 15 is provided with nut-engaging recesses at its ends while the bar 16 is shown as having a nut-engaging recess on one end, and as having its other end in the form of a screw driver. The bar 15 is also shown as having thumb-engaging recesses 18, by means of which it can be more readily slid back and forth, since the operator can hold a tool in one hand and with the thumb of that hand manipulate the slide bar. The bar 16 can, of course, be provided with similar recesses.

It will be apparent that for nuts in the larger sizes, the slides 15 and 16 will be permitted to remain in the retracted position shown in full lines in Figs. 1 and 2, and the ends 11 and 12 of the main bar utilized to turn such nuts. The wrench will probably be made of convenient pocket size, and if greater leverage is required than that possible with the limited length of the bar 10, one of the slides 15—16 may be projected in a direction away from the nut and utilized as a lever.

For nuts of the next smaller size, the bar 15 may be slid to the position indicated by dotted lines in Fig. 1, while for still another smaller size, it will be correspondingly slid in the opposite direction. The bar 16 is also slideable in either direction to bring its nut-engaging end or its screw driver portion into operative position.

In Fig. 4, I show an arrangement similar to that of Figs. 1 to 3, but wherein additional slides are provided, in order to furnish a greater number of tools. Whereas, in Figs. 1 and 2, six tools are provided, two on each of the three bars, in Fig. 4 I provide five bars. The main bar 20 corresponds to the bar 10 of Figs. 1 to 3 and is provided with pairs of flanges 21 and 22 that are grooved for the reception of slides 23, 24, 25 and 26, which slides correspond to the slides 15 and 16. The edges of the slides 23 to 26 are supported in the grooves of the flanges 21—22 and the slides have longitudinal slots through which a pin 27 extends to limit their sliding movements. The pin 27 is shown as having a drive fit with a hole in the main bar 20. As in the case of the slides 15 and 16, the slides 23 to 26 are selectively operable to bring their ends into operative position.

Referring now to Figs. 5 and 6, I show a main bar 30 that corresponds to the bar 10 of Fig. 1, but whose flanges 31 and 32 are not bent inward as are the flanges 13 and 14 of Fig. 3. In the device of Fig. 6, slides 33

110

and 34 are held in place by the heads of a rivet member 35 that has a drive fit with a hole in a bar 30 and loosely engages the bars 33 and 34 to permit sliding movement thereof. The bars 33 and 34 are provided with slots corresponding to those in the bars 15 and 16.

In Figs. 7 and 8, the main bar 36 has pairs of flanges 37 and 38 between which bars 39 and 40, that correspond to the bars 15 and 16, are slidably supported. Portions of the flanges 37 and 38 are peened inwardly as indicated at 41, to partially overlie the slides 39 and 40 and prevent such slides from falling out of place. Longitudinal movement of the slides 39 and 40 is limited by a pin 42 that extends through the bar 36.

From the foregoing it will be seen that I provide a multipart wrench of simple and compact form, whose various parts have tool-engaging portions at each end, so that for a given thickness of structure, I am enabled to provide for operation of a maximum number of sizes of nuts. If the slides were each provided with a nut-engaging member on only one of its ends, it will be seen that a structure of twice the thickness would be required, with the result that for some nut sizes, the wrench could not be brought into proper radial alinement with the nut, but that the wrench would lie at a too greatly inclined position to properly engage such nuts. It will also be seen that considerable leverage over that permissible with the length of the main bar is possible through extension of one of the slides, or that for nuts of smaller sizes, one of the slides can be projected in one direction to engage the nut, and the other slide projected in the other direction to provide the desired leverage.

I claim as my invention:—

1. A tool comprising a bar having a nut-engaging recess in each end and serving as a grip member, the bar having a longitudinally-extending exposed channel in one side, and a second bar slidably supported in said channel and having a nut-engaging recess on each end, the second bar being of shorter length than the distance between the first-named recesses, but movable to such positions that each of its ends will project beyond the adjacent ends of the first-named bar, and each of said nut-engaging recesses being complete in itself for the turning of a nut.

2. A tool comprising a bar having a longitudinally-extending exposed channel, and a second bar slidably supported in said channel and having tool members formed on its ends, the second bar being of shorter length than the first-named bar but movable to such positions that each of its ends will project beyond the adjacent end of the first-named bar, and each of said tool members being complete in itself.

3. A tool comprising a bar having a longitudinally-extending exposed channel in two opposite sides, and another bar slidably supported in each of said channels and having tool members formed on its ends, the second-named bars being each of shorter length than the first-named bar but movable to such positions that each of its ends will project beyond the adjacent end of the first-named bar, and each of said tool members being complete in itself.

In testimony whereof I, the said FREDRICK SIEVERN, have hereunto set my hand.

FREDRICK SIEVERN.
